UNITED STATES PATENT OFFICE.

EDWIN CLEARY, OF LONDON, ENGLAND; ALFRED HUTCHISON ADMINISTRATOR OF SAID EDWIN CLEARY, DECEASED.

OVEN, HOT PLATE, BAIN-MARIE, AND THE LIKE.

Application filed May 12, 1922. Serial No. 560,352.

To all whom it may concern:

Be it known that I, EDWIN CLEARY, a citizen of the United States of America, residing at London, England, have invented 5 new and useful Improvements Relating to Ovens, Hot Plates, Bains-Marie, and the like, of which the following is a specification.

This invention relates to ovens, cookers, hot plates, bains marie, and the like, chiefly 10 designed for domestic use and more especially adapted to be heated by petroleum stoves, gas burners and the like.

According to the invention the oven comprises an inner casing or oven chamber 15 mounted in an outer casing so as to leave an intermediate space between the casings, the outer casing being provided at its lower end with an inlet aperture for the hot gases from a burner and at its upper part with 20 one or more outlets for the cooled gases. A water bath arranged in the upper part of the intermediate space communicates with the exterior through holes in the top plate of the outer casing, and a circulation pipe 25 has its ends in communication with the interior of the water tank and extends into the part of the intermediate space between the bottom walls of the casings.

The circulation pipe is advantageously 30 made in the form of a loop, ring or coil extending around the hot gas inlet aperture in the bottom wall of the outer casing, one vertical limb of the circulation pipe being made of larger diameter than the other, so 35 as to induce a circulation of water in the system.

The top and bottom walls of the outer casing may be advantageously made with 40 flanges fitting over the side walls of such casing and be held in position by bolts or the like. Moreover the part of the bottom wall of the inner casing or oven chamber opposite the inlet for the hot gases is suitably protected, for example by means of a 45 disc of cast iron secured to its underside.

If desired, a plurality of my improved 50 ovens may be arranged side by side with their hot gas or intermediate spaces in communication with each other, means such as sliding doors or dampers being provided for closing one or more of the hot-gas-inlet-apertures of such ovens, in accordance with the number of burners required for producing the temperature necessary for the cooking 55 operation in progress.

The accompanying drawings show how the invention may be conveniently and advantageously carried into practice. In these drawings:-

Figure 1 is a front elevation, 60

Figure 2 a transverse section on the line 2-2, Fig. 4, and

Figure 3 a transverse section taken in a plane perpendicular to the plane of section in Figure 2, its upper part on the line 3-3, Fig. 4, and its lower part on the line 3-3, Fig. 5;

Figure 4 is a plan and

Figure 5 a horizontal section on the line 5-5, Fig. 3, of a cooker constructed according to my invention. 70

The internal casing or chamber A of the oven is arranged in an outer casing B in such a manner that a space is left between the casings on all sides except at the front where the door C is arranged. The outer casing B has an aperture D in its bottom B'' to admit the flame from a petroleum or gas burner, e. g. such as that described in the specification of my former Letters Patent No. 1,381,080. 75

The hot gases pass from the interior of the hollow bottom up the spaces between the inner and outer casings A, B into the space above the inner casing beneath a water tank E which fills the major portion of the space between the upper walls or top plates of the inner and outer casings and may advantageously be formed of galvanized sheet iron. From this space, the gases pass up a space F at the front of the water tank and out to the exterior through apertures G, G formed in the upper part of the front wall H of the outer casing above the door C. These outlet apertures are covered by screens J, J of wire gauze, perforated metal or the like. 85

The water tank is open at the top to the exterior through apertures K, K formed in the upper wall or top plate B' of the outer casing, each of these apertures serving to receive the body of a suitably shaped saucepan, steamer, or other cooking vessel L, a kettle, or the like, or serving to allow the steam from the water tank to act directly on and heat the underside of a cooking or other vessel placed on the upper wall B', which thus forms a hot plate. The underside of the top plate B' is provided with strengthening ribs or the like to enable it to sustain 100 105 110

- the weight of the cooking vessels, kettles, or other objects to be heated thereon. The said cooking vessels, kettles, or the like are preferably made so as to fit closely in or over the apertures K, K so as to prevent escape of the steam from the water in the tank. Moreover, the apertures in this plate are preferably provided with strengthening rings or ribs M, M to enable them to resist wear. From the bottom of the water tank a copper or other suitable metal pipe N extends down one of the spaces between the vertical walls of the inner and outer casings, preferably the space between the rear walls, into the space between the bottoms of the casings and is extended by a similar pipe N' of smaller diameter into a loop arranged around the aperture D in the bottom of the outer casing. The other end of this pipe N' extends up through e. g. the same back space between the two casings and communicates with the interior of the tank E. By making the vertical limb N of the pipe of larger diameter than the other part N' of the pipe, a circulation of water is induced in the system. In order to prevent spurting upwards of the hot water from the circulation pipe N', a baffle O is arranged in the tank E above the outlet of this pipe. A pipe 2 extends from the lowest point of the pipe N to an external tap 3, whereby the water can be readily drawn off from the tank E and circulation pipes N, N' when required. In order to vary the temperature in the oven, holes P, P are formed in the upper wall or top plate A' and a similarly perforated strip Q is arranged to slide so as to bring the holes R, R therein into and out of register with the holes P, P a part of the strip extending to the exterior where it is provided with an operating handle Q'. By this means the hot air in the interior of the oven chamber may be allowed to escape into the intermediate space and allow cool air to enter from the exterior. The door C has a window S of glass, mica or other suitable material to enable the contents of the oven to be observed from the exterior. The door C is hinged at C' and is retained in its closed position, e. g. by means of curved springs arranged near the top and engaging behind fixed projections on the oven, the springs yielding when the door is opened and closed. Moreover a thermometer T is provided in the interior of the oven chamber and is arranged so that its scale is visible from the exterior through the window S in order to enable the temperature of the oven to be controlled in accordance with the food to be cooked. A list of temperatures suitable for different foods may be provided on the exterior of the oven. The top and bottom walls or plates B', B''

of the outer casing are made with flanges V, V sliding over the side walls B of this casing, so as to enable the interior of the spaces between the casings to be exposed for cleaning, inspection, etc. These top and bottom walls may be held in position by means of bolts W, W extending through the spaces between the two casings.

The door C, the interior casing A, and the shelves Y, Y therein may be advantageously made of aluminium or aluminium alloy and the bottom or underside wall of such interior casing may be advantageously protected at the place where the flame from the burner impinges on it. For example, it may have a disc Z of cast iron or other heat resistant metal secured to its underside, e. g. by bolts or rivets. The outer casing may advantageously be formed of sheet iron, e. g. charcoal iron.

The oven is provided with suitable feet or legs 1, 1 secured e. g. by bolts to the bottom plate of the outer casing.

What I claim is:

1. A cooking apparatus comprising an oven-chamber, a door to said chamber, an outer casing surrounding said chamber so as to leave an intermediate space around the oven-chamber, said outer casing having a hot-gas inlet-aperture in its bottom and an outlet at its upper part for the cooled gases, a water bath extending to the top of the intermediate space, and which communicates with the exterior through holes in the top plate of the outer casing, and a circulation pipe the ends of which communicate with the interior of the water tank and which extends into the part of the intermediate space between the oven-chamber and the bottom of the outer casing where it is formed into a loop arranged around the hot-gas inlet-aperture, one vertical limb of said pipe being of larger diameter than the other.

2. A cooking apparatus comprising an inner casing forming an oven-chamber, a door to said chamber, an outer casing surrounding the vertical sides of said inner chamber except that containing the door, and also enclosing the bottom wall of the oven-chamber, an intermediate space being left between said casings and the bottom wall of the outer casing having a hot-gas inlet-aperture, the lower wall of the oven chamber having a reinforcement opposite said hot-gas inlet-aperture, the outer casing having a top plate provided with an opening, a water-tank communicating with the exterior through said opening in the top plate of the outer casing and which is arranged at a short distance above the oven-chamber so as to leave an intermediate space in communication with the intermediate space between the inner and outer casings, the combined intermediate space having a gas outlet, and a circulation pipe the ends of which

communicate with the interior of the water tank and which extends entirely through the intermediate space into the part of the intermediate space between the oven-chamber and the bottom of the outer casing, one vertical limb of such pipe being of larger diameter than the other.

3. A cooking apparatus comprising an inner casing forming an oven-chamber, a door for said chamber, an outer casing surrounding said inner chamber so as to leave an intermediate space between said casings, said outer casing having a hot-gas inlet aperture in its bottom and a gas outlet from 10 said intermediate space, separate top and bottom walls for said outer casing having flanges for embracing side walls of said casing, means for detachably holding said

top and bottom walls in position on said side walls, said top wall having an opening, 20 a water bath arranged in the upper part of the intermediate space and communicating with the exterior through said opening in the top wall of the outer casing, and a circulation pipe of which the ends communicate with the interior of the water tank and which extends entirely through the intermediate space between the oven-chamber and the bottom of the outer casing, one vertical 25 limb of said pipe being of larger diameter than the other.

EDWIN CLEARY.
